COIN COMPARTMENTS, COIN VAULTS OR
COIN STORAGE ASSEMBLIES

Clarence D. Fayling, Pittsburgh, Pa., and Jack A. Prickett,
Russellville, Ark., assignors to Rockwell Manufacturing
Company, Pittsburgh, Pa., a corporation of Pennsylvania

Filed Aug. 17, 1965, Ser. No. 480,426
6 Claims. (Cl. 232—15)

This invention relates to coin compartments or coin vaults for parking meters and other coin operated devices.

In general, coin operated parking meters comprise a housing enclosing a timing mechanism and an indicator mechanism in an upper section and a coin storage compartment or vault in a lower section. Coins inserted into the upper section actuate the timer and indicator mechanism and then pass downwardly into the coin storage compartment where they are retained until they are removed by a coin collector.

Since parking meters are notoriously attractive targets for vandalism and robbery they must be of exceptionally rugged construction. Also, they must be readily openable to permit frequent collection of coins and to permit removal of the coins rapidly and conveniently.

At present there are several different systems available for coin collection. Some require that the door of the coin box be hinged at the top of the door opening for "dump" collection and others require that the door be hinged at the bottom of the door opening for use with a removable coin box. Prior to the present invention parking meters have been constructed to permit their use with one coin collection system or other, but not with both. Accordingly, in many cases the replacement of existing parking meters or the addition of new meters requires either substantial revision of the meter structure or the adoption by the city of two different coin collection systems.

It is also important in the construction of parking meters that the coin compartment door, when closed and locked, have essentially the same resistance to breakage or unauthorized opening as one of the solid walls of the coin compartment itself. The door and the adjacent coin compartment structure must be so constructed that the door can neither be removed by prying outwardly nor by being driven inwardly. The lock structure must be similarly resistant to mechanical damage by impact or by drilling.

With these considerations in mind it is a principal purpose and object of the present invention to provide improved coin compartment and door structure for parking meters and similar coin operated devices which satisfy the foregoing requirements to a degree not heretofore available in the art.

It is a further object of the present invention to provide unique coin storage compartment and door constructions which permit the door to be pivoted either at the top or bottom of the door opening and in which the door may be quickly and easily reversed without modification of the door or the compartment or the removal or addition of parts or without use of conventional hinges and hinge pins.

It is also an object of the present invention to provide coin compartments and reversible doors for the compartments in which the reversibility is achieved without sacrificing the ruggedness and vandal-resistant characteristics of the structure.

It is an additional object of the present invention to provide improved coin vaults and reversible doors in which the reversibility is achieved without requiring addi-

2

tional parts and without increasing the cost of the structure.

It is a further object of the present invention to provide improved locking assemblies for coin compartment doors which are relatively simple and of inexpensive construction and which provide an unusual degree of resistance to breakage or disabling.

Additional objects and advantages of the present invention will become apparent as the description proceeds in connection with the accompanying drawings in which:

FIGURE 1 is a front view of a parking meter assembly including a coin vault and door embodying the present invention;

FIGURE 2 is a central vertical section taken along line 2—2 of FIGURE 1;

FIGURE 3 is a fragmentary interior view looking in the direction of the arrows 3—3 in FIGURE 2;

FIGURE 4 is a fragmentary horizontal section taken along line 4—4 of FIGURE 1; and

FIGURE 5 is a view similar to FIGURE 2 showing the door in inverted position.

Referring now more particularly to the drawings the parking meter assembly indicated generally at 20 includes an upper section 22 housing the usual timing and indicator mechanism and a lower coin vault section indicated generally at 24. The entire assembly is adapted to be securely mounted on a post 26 by means not shown.

The upper section 22 has the usual coin receiving slot 27 through which coins are inserted to set time on the meter. The coins inserted into the meter are either positively driven or pass by gravity into the coin box 24 with which the present invention is primarily concerned.

The coin vault 24 is of one piece construction and is fabricated of malleable iron having maximum impact resistance. The vault is formed with a top wall 28 having an opening, not shown, for the reception of coins from the upper meter section, an essentially flat back wall 30, opposed side walls 32 and 34, and a horizontal bottom wall 36 including mechanism, not shown, for attachment to the supporting post 26. The front wall 37 of the coin vault has an opening 38 normally closed by the door assembly indicated generally at 40. The top and bottom edges of the opening are of essentially the same construction and comprise lips 42 and 44 projecting inwardly from the front wall of the box, the lip 42 terminating at its inner end in a downwardly projecting ledge 46 and the lip 44 terminating at its inner end in an upwardly projecting ledge 48. As is best shown in FIGURE 4 the sides of the opening are provided by a reinforced front portion of the side walls 32 and 34 and comprise inclined flat portions 50 and 52 terminating at their inner edges in the aligned ledges 54 and 56, respectively, which are essentially parallel to the front and rear surfaces of the coin compartment and are co-planar with the ledges 44 and 46. Thus, the door opening is bounded by a ledge 55 which is offset inwardly a substantial distance from the front face of the coin vault.

The door 40, which is fabricated from impact resistant malleable iron, is so formed that when it is closed, as shown in FIGURES 2 and 4, it fits closely within the recess provided in the front of the compartment. Thus, at its top edge it has inclined surface 58 fitting closely against the surface of the lip 42, and inclined side surfaces 60 and 62 conforming closely to the side surfaces 50 and 52, respectively, of the opening.

The bottom edge of the door fits securely against the outer surface of the ledge 44 but is rounded as at 63 to facilitate a pivotal hinge type action as described below. The door is also formed along its top and side edges with co-planar surfaces 64, 66 and 68, which fit securely against the outer surfaces of the ledges 46, 54 and 56, respectively. At its bottom edge the rounded

projection 63 of the door bears against the outer surface of the lip 44. Because of mounting of the door in the recessed front opening it is virtually impossible to insert a prying tool into the space between the door and the door opening to force the door outwardly. Similarly, because of the peripheral ledge construction and the inclined top and side surfaces of the door opening, the door cannot be driven inwardly into the compartment.

At its lower edge as viewed in FIGURE 2, the door is provided with a heavy integral lip 70 which extends around the inner edge of the ledge 48. This construction holds the door rigidly against outward movement and yet permits the door to swing freely from its closed position shown in full lines in FIGURE 2 to its open position shown in dotted lines.

The door 40 is guided for swinging movement by a pair of arcuate arms 71 and 72 which are formed integrally with a base 73 secured by screws 74 to the interior of the door. The arms are slotted as at 75 to receive studs 76 carried by the coin compartment side walls 32 and 34, respectively. These arcuate arms 71 and 72 are retained on studs 76 by snap rings 76a.

The door is normally held in closed position by the lock assembly indicated generally at 77 which will now be described in detail with particular reference to FIGURES 2 and 3. The lock assembly includes a hardened steel bolt 78 slidably in aligned bores 79 and 80 formed in bosses 81 and 82 formed integrally with the body of the door. In its locked position shown in FIGURE 2, the bolt 78 projects behind the adjacent edge of the coin vault wall. In its retracted position the end of the bolt is substantially flush with the end of the boss 81. The bolt 78 also projects through aligned openings 84 and 86 in the inner end of a retainer sleeve 88 positioned in a bore 90 extending through the door.

A key operated lock assembly 92 is carried by the sleeve 88 and comprises an outer housing 94 having a slot 96 for the reception of a set screw 98 which is adjusted through an opening 100 to lock the housing 94 to the sleeve 88. The housing 94 supports a rotatable cam 102 carrying an eccentric pin 104 which extends into a notch 106 in the bolt 78. Below the notch the bolt is cut away to provide a flat 108 to facilitate assembly for the parts. After assembly, a roll pin 110 is pressed into a bore in the bolt 78 to increase the effective depth of the notch 106 along its lower side.

The lock per se, which may take a number of conventional forms, is effective to hold the cam 102 against rotation with respect to the housing 94 or to permit limited rotation of the cam and the associated pin 104 in a clockwise direction as viewed in FIGURE 3 thereby displace the bolt 78 between locked and unlocked positions.

This lock assembly is of exceptionally rugged construction and cannot be pried open or loosened without complete destruction of the door. The lock assembly cannot be driven inwardly through the door since its path in this direction is blocked by the bolt. It cannot be withdrawn outwardly since it is held in place by the annular lip 112 on the sleeve 88 which is in turn held against outward movement by its engagement with the bolt 74.

As stated above there are certain coin collection systems which require that the door be pivoted at the bottom as shown in FIGURE 2. In other systems it is desirable that the door be pivoted at the top. Such an installation is shown in FIGURE 5. It is a feature of the invention that the door may be originally installed in either position, or once installed, may be quickly and easily reversed. To reverse the door from either position it is necessary only to open the door, remove snap rings 76a, spring the arms 71 and 72 inwardly sufficiently to clear the studs 76, reposition the door in reverse orientation and snap the arms 71 and 72 onto the studs and replacing the snap rings 76a. Since the top and bottom edges of the door opening are of the same configuration

and dimensions the operation of the hinge and lock is the same in either position of the door.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by Letters Patent is:

1. A coin storage assembly for a coin operated device comprising, a coin compartment having a front wall, means forming an inwardly tapering recess in said front wall, said recess terminating at its inner end at a first ledge peripherally bounding an opening in said front wall, a door adapted to selectively close said opening, said door having a second ledge adapted to abut said first ledge when the door is closed, and said door having tapered peripheral surfaces closely fitting said recess, a lock carried by said door at one end thereof for selective locking engagement with said front wall of said compartment adjacent either end of said door opening, a lip rigid with the opposite end of said door for rocking engagement with either end of said door opening, said lip and each end of said door opening being formed to provide a hinge connection about which said door may be swung between open and closed positions, and arcuate arms carried by said door and detachably engageable with the side walls of said door opening to guide said door in its swinging movements.

2. The coin storage assembly according to claim 1 wherein the opposite ends of said door opening are of identical construction whereby said door may be reversed end for end within said opening to dispose the lip at either selected end of said opening, said arms being operable in either position of said door.

3. The coin storage assembly according to claim 1 wherein said lip projects beyond the end of said door opening for engagement with the inner surface of the adjacent portion of said first ledge when said door is closed.

4. The coin storage assembly according to claim 1 wherein said block includes a locking bolt slidably carried by said door for movement in a direction normal to the adjacent edge of said door opening for selective engagement with the inner surface of the adjacent portion of said first ledge.

5. The combination according to claim 1 wherein said lock comprises a locking member slidably carried by said door for movement into and out of engagement with the inner surface of said front wall, a rotatable member carried by said door and operatively connected to move said locking member, lock means for selectively locking said rotatable member against rotation, and a lock retainer carried by said door, the inner end of said retainer encircling said locking member to prevent withdrawal of said retainer, and the outer end of said retainer engaging the outer end of said lock means to prevent withdrawal of said lock means.

6. In a coin storage assembly including a coin compartment having a door opening in a front wall thereof, a door swingable about a lip means at one end of said opening, a boss at the opposite end of said door, said boss having a pair of aligned openings, a locking member slidably received in said openings for movement into and out of engagement with the inner surface of said front wall, a rotatable member carried by said door and operatively connected to move said locking member a lock assembly for selectively locking said rotatable member against rotation, and a lock retainer carried by said door, the inner end of said retainer encircling the portion of said locking member between said openings to prevent

withdrawal of said retainer, and the outer end of said retainer engaging the outer end of said lock assembly to prevent withdrawal of said lock assembly.
